POLARIZED ELECTRICAL RELAY

Thomas J. O'Meara, Swissvale, Pa., assignor to
The Union Switch & Signal Company, Swiss-
vale, Pa., a corporation of Pennsylvania

Application October 17, 1944, Serial No. 559,076

10 Claims. (Cl. 175—339)

1 My invention relates to electrical relays, and particularly to electrical relays of the direct current polarized type. More particularly, my present invention relates to polarized relays having two oppositely polarized armatures so arranged that both armatures will be released or one armature or the other will be picked up according as the relay is deenergized or is energized by current of one polarity or the other.

One object of my invention is to provide a relay of the type described with means for positively preventing either armature from moving to its attracted position for any reason when the other armature occupies its attracted position to thereby increase the safety of the relay against false operation.

Another object of my invention is to provide a polarized relay having increased immunity to false operation due to overenergization, lightning surges, and the like.

A further object of my invention is to provide a relay of the type described which is simple to construct and maintain.

In accordance with my invention these objects are obtained by mounting the two armatures of the relay in close proximity, and by associating with the armatures suitable means for interlocking them in such manner that the picking up of either armature locks the other armature in its released position.

Other objects and characteristic features of my invention will become apparent as the description proceeds.

I shall describe three forms of electrical relays embodying my invention, and shall then point out the novel features thereof in claims.

In the accompanying drawings, Fig. 1 is a view partly diagrammatic and partly in isometric projection showing one form of relay embodying my invention. Figs. 2 and 3 are views similar to Fig. 1 showing modified forms of the relay illustrated in Fig. 1.

Similar reference characters refer to similar parts in each of the several views.

Referring first to Fig. 1, the relay here shown comprises a first magnetic circuit consisting of two magnetizable pole pieces 1a and 2a connected at their upper ends by a magnetizable backstrap 3a and provided at their lower ends with inwardly extending portions 4a and 5a, and a second magnetic circuit consisting of two magnetizable pole pieces 1b and 2b connected at their upper ends by a magnetizable backstrap 3b and provided at their lower ends with inwardly extending portions 4b and 5b. Both magnetic circuits are en-

2 ergized by a common winding 6 which surrounds the two back straps 3a and 3b between the associated pole pieces. The inwardly extending portions of both sets of pole pieces have their lower or pole faces ground to lie in the same plane for a purpose which will be made clear presently.

The relay also comprises a magnetizable armature 7a which is pivotally mounted adjacent one end for swinging movement toward and away from the pole faces of the pole pieces 1a and 2a, and a magnetizable armature 7b which is pivotally mounted adjacent one end for swinging movement toward and away from the pole faces of the pole pieces 1b and 2b. The armature 7a is operatively connected with a plurality of contact fingers 9a and 10a shown diagrammatically in the drawing, in such manner that, when the armature is swung away from the pole pieces 1a and 2a the fingers 9a and 10a will engage fixed back contact members 11a and 12a, respectively, to close back contacts 9a—11a and 10a—12a, but that, when the armature is swung toward the pole pieces, the contact fingers will then move out of engagement with the back contact members and into engagement with fixed front contact members 13a and 14a to open the back contacts and close front contacts 9a—13a and 10a—14a, respectively. The armature 7b is similarly connected with contact fingers 9b and 10b which cooperate with fixed back contact members 11b and 12b or fixed front contact members 13b and 14b to close fixed back contacts 9b—11b and 10b—12b or fixed front contacts 9b—13b and 10b—14b, according as the armature 7b is swung toward or away from the pole pieces 1b and 2b. The physical structure of the contact fingers and associated fixed contact members and the means for connecting them with the associated armatures are well known, and need not therefore be described in detail herein.

40 The relay further comprises two L-shaped permanent magnets 15a and 15b for polarizing the armatures 7a and 7b. The magnet 15a is secured at one end to the pole piece 2a, and the other end of this magnet extends underneath the armature 7a opposite the pole face of the pole piece 2a in such manner that, when the armature 7a is swung away from the pole pieces 1a and 2a, it will be swung toward the permanent magnet 15a, and vice versa. In actual practice, the armature 7a will be prevented from actually touching the pole pieces 1a and 2a, or the permanent magnet, by suitable non-magnetic stops or core pins not shown in the drawing.

45 The magnet 15b is secured to the pole piece 2b and cooperates with the armature 7b in the same

3
manner that the magnet 15a is secured to the pole piece 1a and cooperates with the armature 7a.

Associated with the armatures 7a and 7b are suitable means for interlocking them in such manner that the picking up of either armature will lock the other armature in its released position. This interlocking means may have any desired construction and may be located at any convenient location, but as here shown this means comprises a non-magnetic interlocking dog 16 pivotally supported intermediate its ends between the ends of the armatures on a pivot pin 17 and cooperating at its ends with two laterally projecting ears 18a and 18b secured to the two armatures 7a and 7b, respectively. The pivot pin 17 is secured to a suitable non-magnetic supporting member disposed between the two pole pieces 2a and 2b, respectively.

Assuming that the upper end of the permanent magnet 15a is a north pole and the upper end of the magnet 15b is a south pole, as indicated by the letters N and S in the drawings, the operation of the relay as a whole is as follows: Only when the winding 6 is deenergized, both armatures 7a and 7b will drop, under the influence of gravity, to the positions shown, so that the back contacts 9a-11a, 10a-12a, 9b-11b and 10b-12b will all be closed, and under these conditions, a part of the flux from each of the permanent magnets 15a and 15b will pass lengthwise through the associated armature 7a or 7b and will exert on the armature a torque which assists the pull of gravity in holding the back contacts closed. The parts are so proportioned that this torque, together with the force of gravity, will be sufficient to prevent the back contacts from bouncing open even though the relay is subjected to considerable shock or vibration.

I shall now assume that the winding 6 is energized in such manner that the pole pieces 2a and 2b become north poles and the pole pieces 1a and 1b become south poles. Under these conditions the permanent magnet and electromagnet fluxes will buck each other in the armature 7a and will aid each other in the armature 7b. As a result, as the magnetomotive force builds up in armature 7a, a point will be reached at which the upward pull exerted on the armature 7a by this flux will exceed the downward pull due to the permanent magnet flux and the force of gravity, and when this happens the armature 7a will swing toward the pole pieces 1a and 2a to thereby open the back contacts 9a-11a and 10a-12a and to close the front contacts 9a-13a and 10a-14a. The armature 7b, however, will be held more strongly in its released position, and this will be true even though the energization of winding 6 is increased to many times its normal value. The picking up of the armature 7a will act through the ear 18a to rotate the interlocking dog 16 in a clockwise direction as viewed in Fig. 1 to a position in which it will just clear the upper face of the ear 18b attached to armature 7b, and consequently the armature 7b, in addition to being held in its released position by the pull of gravity and the combined fluxes due to the electromagnet and permanent magnet traversing this armature, will be effectively locked in its released position.

If the winding 6 is energized in such manner that the pole pieces 2a and 2b become south poles and the pole pieces 1a and 1b become north poles, the armature 7b will then pick up and the armature 7a will remain in its released position, as will be obvious. Furthermore, the picking up of the

4
armature 7b will act through the ear 18b to rotate the dog 16 in a counterclockwise direction to the position in which it cooperates with the ear 18a to lock the armature 7a in its released position.

It will be seen, therefore, that with a relay constructed in accordance with my invention when winding 6 is deenergized both armatures 7a and 7b will be held in their released positions by flux from the permanent magnets, whereas when the winding 6 is energized, one armature or the other will pick up, depending on the polarity of the current supplied to the winding 6. It will also be seen that the armature which does pick up will act to lock the other armature in its released position.

Referring now to Fig. 2, I have here shown a modified form of relay which differs from that shown in Fig. 1 principally in the fact that a single magnetic circuit is provided for controlling both armatures, which armatures as illustrated are pivoted at opposite ends of the relay instead of at the same end. These armatures could, however, be pivoted at the same end of the relay if desired. As illustrated, the single magnetic circuit comprises two pole pieces 21 and 22 attached at their opposite ends to a backstrap 23. The energizing winding 6 is mounted on the backstrap 23 between the two pole pieces 21 and 22. The pole pieces are made large enough to overlie both armatures and the two permanent magnets 15a and 15b are secured to the pole pieces 21 and 22, respectively, in laterally offset relation in positions to cooperate with the free ends of the armatures in the same manner as in Fig. 1. The interlocking dog 16 is pivotally supported from the pole piece 21 by means of a bracket 24 and pivot pin 25 in a position which is laterally between the two armatures approximately midway between their ends.

The operation of the relay shown in Fig. 2 is essentially the same as the operation of the relay shown in Fig. 1, and will be obvious from the foregoing description and from an inspection of the drawing without further detail description.

Referring now to Fig. 3, the relay here illustrated comprises a magnetic circuit consisting of two parallel cores 25 and 26 connected together at their upper ends by a backstrap 27, and provided at their lower ends with enlarged pole pieces 28 and 29 to which the L-shaped permanent magnets 15a and 15b are respectively attached. The cores 25 and 26 carry the usual operating windings 6a and 6b. The two magnetizable armatures 7a and 7b are pivotally mounted end to end in such manner that the armature 7a is free to swing between the pole piece 28 and the permanent magnet 15a and that the armature 7b is free to swing between the pole piece 29 and the magnet 15b. The confronting ends of the armatures 60 are in good magnetic transfer relationship, and carry interlocking means effective upon the movement of either armature toward the associated pole piece to prevent the other armature from moving toward the associated pole piece. As 65 illustrated, these interlocking means comprise two similar arms 31 and 32 attached to the armatures 7a and 7b, respectively, and provided with stop pins 31a and 32a so disposed that when either armature is picked up it will move the associated 70 stop pins into engagement with the other stop pins and thus act to prevent the other armature from picking up. The armatures 7a and 7b may operate contacts in the same manner as in Figs. 1 and 2. The permanent magnets are arranged 75 so that their upper ends both have the same

polarity, this polarity being assumed to be north for purposes of explanation, as indicated by the letters N in the drawing.

With the relay constructed in this manner, aside from the fact that any flux which is set up due to energization of the windings 6a and 6b traverses the two armatures in series the operation of the relay as a whole is essentially the same as that of the relays shown in Figs. 1 and 2. That is to say, when the windings 6a and 6b are both deenergized, both armatures will occupy their released positions as shown. When, however, the windings 6a and 6b are energized, one armature or the other will pick up depending on the polarity of the current, the other armature under these conditions being held down both by the attraction of the associated permanent magnet and also by the action of the interlocking means comprising the stop pins 31a and 32a.

Although I have herein shown and described only three forms of electrical relays embodying my invention, it is understood that various changes and modifications may be made therein within the scope of the appended claims without departing from the spirit and scope of my invention.

Having thus described my invention, what I claim is:

1. A relay comprising two pairs of pole pieces, means including an energizing winding and a back strap for supplying flux to the pole pieces of both pairs, two armatures one pivotally mounted for swinging movement toward and away from the pole pieces of each pair, two permanent magnets one secured directly to the pole piece located at the free end of each armature and having its one pole disposed in such a position with respect to the associated armature that when it is swung away from the associated pole pieces it will be swung toward said one pole of the associated magnet, and mechanical means effective upon the picking up of either armature for locking the other armature in its released position.

2. A relay comprising two magnetic circuits each comprising a pair of pole pieces connected to a backstrap, an energizing winding surrounding said backstraps for reversibly supplying flux to both magnetic circuits, two armatures one pivotally mounted at one end for swinging movement toward and away from the pole pieces of each pair, two permanent magnets one secured directly to the pole piece located at the free end of each armature and having its one pole disposed in such a position with respect to the associated armature that when it is swung away from the associated pole pieces it will be swung toward said one pole of the associated magnet, said permanent magnets being magnetized to cause said armature to respond to currents of opposite polarity in said winding, and mechanical means effective upon the picking up of either armature for locking the other armature in its released position.

3. A relay comprising two magnetic circuits each comprising a pair of pole pieces connected to a backstrap, an energizing winding surrounding said backstraps for reversibly supplying flux to both magnetic circuits, two armatures one pivotally mounted at one end for swinging movement toward and away from the pole pieces of each pair, two permanent magnets one secured directly to the pole piece located at the free end of each armature and having its one pole disposed in such a position with respect to the asso-

ciated armature that when it is swung away from the associated pole pieces it will be swung toward said one pole of the associated magnet, said permanent magnets being magnetized to cause said armature to respond to currents of opposite polarity in said winding, and an interlocking dog pivotally supported intermediate its ends between said armatures and cooperating at its ends with two laterally projecting ears secured to the two armatures respectively in such manner that movement of either armature to its picked-up position will act through the associated ear to rotate said dog to a position in which it cooperates with the other ear to lock the other armature in its released position.

4. A relay comprising two pole pieces secured to a backstrap surrounded by an energizing winding, two armatures pivotally supported side by side at their opposite ends underneath said pole pieces for swinging movement toward and away from said pole pieces, two permanent magnets one secured to each pole piece and having its one pole disposed in such a position with respect to the end of the armature which is free to swing toward and away from such pole piece that when it is swung toward the pole piece it will swing toward said one pole of the associated magnet, and mechanical means effective upon the picking up of either armature for locking the other armature in its released position.

5. A relay comprising two pole pieces secured to a backstrap surrounded by an energizing winding, two armatures pivotally supported side by side at their opposite ends underneath said pole pieces for swinging movement toward and away from said pole pieces, two permanent magnets one secured to each pole piece and having its one pole disposed in such a position with respect to the end of the armature which is free to swing toward and away from such pole piece that when it is swung toward the pole piece it will swing toward said one pole of the associated magnet, and an interlocking dog pivotally supported intermediate its ends between said armatures and cooperating at its ends with two laterally projecting ears secured to the two armatures respectively in such manner that movement of either armature to its picked-up position will act through the associated ear to rotate said dog to a position in which it cooperates with the other ear to lock the other armature in its released position.

6. An electrical relay comprising two armatures, means associated with said armatures and including a back strap, pole pieces, and an energizing winding for at times supplying flux of the same polarity to both said armatures, two permanent magnets one associated with each armature and connected to the flux supplying means so as to bias the associated armature to its released position, said magnets being arranged to produce fluxes of opposite polarity in the two armatures so that the one armature will move to its attracted position when and only when said winding is energized by current of one polarity and the other armature will move to its attracted position when and only when said winding is energized by current of the opposite polarity, and mechanical means associated with said armatures and effective upon the picking up of either armature to mechanically lock the other armature in its released position.

7. An electrical relay comprising two armatures, means associated with said armatures and including a back strap, pole pieces, and an en-

7

ergizing winding for at times supplying flux of the same polarity to both said armatures, two permanent magnets one associated with each armature and connected to the flux supplying means so as to bias the associated armature to its released position, said magnets being arranged to produce fluxes of opposite polarity in the two armatures so that the one armature will move to its attracted position when and only when said winding is energized by current of one polarity and the other armature will move to its attracted position when and only when said winding is energized by current of the opposite polarity, and an interlocking dog pivotally supported intermediate its ends between said armatures and cooperating at its ends with two laterally projecting ears secured to the two armatures respectively in such manner that movement of either armature to its picked-up position will act through the associated ear to rotate said dog to a position in which it cooperates with the other ear to lock the other armature in its released position.

8. An electrical relay comprising magnetic circuit means including two spaced pole piece means, back strap means connecting the pole piece means, and two armatures extending between the two pole piece means, each armature having one end movable toward and away from one of the pole piece means, an electrical winding surrounding a portion of the magnetic circuit means and effective when energized to produce flux of the same polarity in both armatures, two permanent magnets, one magnet being associated with each armature and magnetically reconnected with the pole piece means with respect to which the armature moves, each magnet acting to bias its associated armature away from its pole piece means, the two magnets being arranged to produce biasing fluxes of opposite polarities in the two armatures so that when the winding is energized the flux produced by it will aid the biasing flux in one armature and oppose the biasing flux in the other, whereby one armature moves to its attracted position when and only when the winding is energized by current of one polarity and the other armature moves to its attracted position when and only when the winding is energized by current of the opposite polarity, and mechanical means associated with the armatures and effective upon the

8

picking up of either armature to mechanically lock the other armature in its released position.

9. An electrical relay as in claim 8, in which said mechanical means includes an interlocking dog pivotally supported intermediate its ends between said armatures and cooperating at its ends with two laterally projecting ears secured to the two armatures respectively in such manner that movement of either armature to its picked-up position will act through the associated ear to rotate said dog to a position in which it cooperates with the other ear to lock the other armature in its released position.
10. An electrical relay comprising two magnetic circuits; each magnetic circuit including first and second spaced pole pieces, a back strap connecting the pole pieces, an armature pivoted at one end adjacent said first pole piece and having its free end movable toward and away from said second pole piece, a third pole piece facing said second pole piece so that the free end of the armature moves between the second and third pole pieces, and means including a permanent magnet connecting the second and third pole pieces to polarize them oppositely; said permanent magnets being oppositely arranged on the two magnetic circuits so that the respective armatures are of opposite polarity, and a single electrical winding surrounding adjacent portions of the two magnetic circuits, each of which portions connects the first and second pole pieces of its associated magnetic circuit so that upon energization of said winding the flux produced thereby opposes the polarizing effect of one permanent magnet on its associated armature and aids the polarizing effect of the other.
